UNITED STATES PATENT OFFICE.

JOHN SCHOLTZ, OF PHILADELPHIA, PENNSYLVANIA, ASSIGNOR OF ONE-THIRD TO STANLEY A. BROZA, OF ORELAND, PENNSYLVANIA, AND ONE-THIRD TO GUSTAVE W. SUNDAY, OF PHILADELPHIA, PENNSYLVANIA.

CARBURETER.

1,366,959.

Specification of Letters Patent.

Patented Feb. 1, 1921.

Application filed August 1, 1919. Serial No. 314,620.

To all whom it may concern:

Be it known that I, JOHN SCHOLTZ, a citizen of Austria, residing at Philadelphia, in the county of Philadelphia and State of 5 Pennsylvania, have invented certain new and useful Improvements in Carbureters, of which the following is a specification.

One object of my invention is to provide an improved carbureter for use in connection with internal combustion engines and to so make my improved carbureter that it will be of extremely simple construction and so that it can be directly connected with a hose or the like to an illuminating gas pipe. 10 Another object is to so construct my improved carbureter that it can be quickly adjusted to vary the amount of air for mixing with the gas and to make the same of comparatively few parts capable of being 15 quickly made, put together or taken apart. 20

These objects, and other advantageous ends which will be described hereinafter, I attain in the following manner, reference being had to the accompanying drawings in 25 which—

Figure 1 is an end elevation of a gas engine, such for example as the gas engine forming a part of my co-pending application for United States patent, and showing 30 my improved carbureter attached thereto,

Fig. 2 is a fragmentary side elevation of Fig. 1,

Fig. 3 is an enlarged central vertical section of my improved carbureter,

Fig. 4 is a transverse section taken on the line 4—4 of Fig. 3,

Fig. 5 is a fragmentary transverse section taken on the line 5—5 of Fig. 3,

Fig. 6 is a transverse section taken on the line 6—6 of Fig. 3,

Fig. 7 is a section of similar nature to Fig. 6 showing the air regulating collar having been moved from the position shown in Fig. 6, and

Fig. 8 and 9 are perspective views of certain of the elements of my improved carbureter.

Referring to the drawings, 10 represents an internal combustion gas engine having 50 a pipe 11 leading thereto for conveying the fuel gas into the engine to be exploded for the purpose of operating the engine in the usual manner.

My present invention includes a hollow

body portion 12 having a cylindrical vertical bore 13 and a screw threaded stem 14 having a passage 15 which communicates with the top of the chamber 16 provided by said bore 13. A cylinder 17 has its upper end fitting within the bore 13 and secured thereto by a screw 18. The bottom portion of the cylinder 17 extends below the bottom 19 of the body portion 12 and has an annular flange 20 at its bottom. A collar 21 rotatably fits on the lower portion of the cylinder 17 and is interposed between the bottom 19 of the body portion 12 and the flange 20. Thus the collar 21 is free to rotate around the cylinder 17 but is prevented from moving longitudinally thereon. The collar 21 has 60 perforations or holes 22 which are adapted to register with holes 23 in the cylinder 17, as clearly shown in Figs. 3, 6 and 7. The cylinder 17 provides an axial passage 23^a which extends vertically and is flared adjacent its upper end to provide a valve seat 24, said valve seat having perforations 25 leading therefrom at an angle opposite to the flare of the seat 24. These perforations 70 at their ends opposite the seat 24 communicate with or lead into an annular groove 26 formed in said cylinder 17, as clearly shown in Figs. 3 and 9. The body portion 12 has a stem 27 extending laterally therefrom and this stem has an inlet passage 28 for the 80 gas, said passage 28 registering with the annular groove 26 of the cylinder 17. The upper end of the stem 27 is notched, as shown at 29, to permit the attachment of a gas hose 30 (see Fig. 1) in the usual manner 85 of attaching gas hose to valve stems or the like. The stem 27 has a cut-off valve 31 rotatably mounted therein for admitting or cutting off gas to the annular groove 26 in the cylinder 17. A valve 32 is positioned 90 within the chamber 16 and has a rod 33 connected thereto, said rod extending vertically through the axial passage 23^a and being freely slidable through a hole 34 in the bottom of the cylinder 17. The lower end of 100 the rod 33 is screw threaded and a ball 35 or other article which is larger than the hole 34 is screwed on the lower end of the rod 33. Outside of the cylinder 17, as clearly shown in Figs. 1, 2 and 3, the valve 32 is 105 adapted to normally rest upon the seat 24 and cover the perforations 25. The axial passage 23^a is of larger diameter than the

diameter of the rod 33 so that there is a space around the rod 33 which communicates at all times with the holes 23.

During the operation of the engine 10 a 5 suction will be intermittently established in the pipe 11 and this suction will operate to raise the valve 32 from its seat 24 and draw gas and air into the chamber 16 through the perforations 25 and axial passage 23^a, and 10 the gas and air which mixes in the chamber 16 will be sucked into the engine through the passage 15 and then through the pipe 11 into the engine. The position of the ball 35, which serves as a limiting nut, determines 15 the amount of opening movement of the valve 32. After the suction has ceased, the valve 32 will drop by gravity and cut off the gas and air supply, due to the engagement of the valve upon the seat 24.

20 The amount of air can be quickly and easily varied by turning the collar 21, for example Fig. 6 shows the position of the collar 21, when the holes 22 are in complete register with the holes 23. Thus it is an 25 easy matter to vary the amount of air admitted so as to secure the proper mixture of the air and gas.

A regulating valve 11^a is included in the pipe 11 and this regulating valve has a lever 30 36 secured thereto, said lever having two arms 37 and 38 projecting therefrom in opposite directions as clearly shown in Fig. 1. These arms are respectively connected by chains 39 and 40 to two oppositely disposed arms 41 and 42; said arms being connected to a handle 43. This handle is rotatably connected to an indicator 44. The indicator 44 is adapted to traverse a dial 45, said dial having graduations 46 thereon. 40 Thus by moving the handle 43, the regulating valve 11^a can be operated to vary the amount of mixture entering the engine.

By fitting the cylinder 17 within the body portion 12 and securing it with the screw 45 18, it is merely necessary to remove the screw 18 in order to permit the collar 21, cylinder 17 and valve 32 to be removed from the body portion for cleaning or repair purposes.

While I have described my invention as 50 taking a particular form, it will be understood that the various parts of my invention may be changed without departing from the spirit thereof, and hence I do not limit myself to the precise construction set 55 forth, but consider that I am at liberty to make such changes and alterations as fairly come within the scope of the appended claims.

Having thus described my invention, what 60 I claim as new and desire to secure by Letters Patent is:—

1. A carbureter including a body portion having a bore extending inwardly from one end and stopping short of the other end; a 65 cylinder adapted to fit within said bore and

having a valve seat spaced from the inner end of the bore to provide a mixing chamber, said body portion including an inlet gas passage communicating with said bore below said valve seat, said cylinder having 70 perforations leading to said valve seat and communicating with said gas inlet passage, said cylinder having an inner passage leading from said valve seat to a position below said first end of the hollow body portion; a valve for engagement with said valve seat, said cylinder having holes extending laterally from said latter passage, said cylinder having a flange spaced below 75 said first end of the body portion; and a collar rotatably surrounding said cylinder and interposed between said flange and said first end of the body portion, said collar having holes adapted to register with said holes in the cylinder for regulating the amount of 80 air passing through said first passage of the cylinder, said body portion having an outlet passage communicating with said mixing chamber; substantially as described.

2. A carbureter including a body portion 90 having a bore extending inwardly from one end and stopping short of the other end; a cylinder adapted to fit within said bore and having a valve seat spaced from the inner end of the bore to provide a mixing 95 chamber, said body portion including an inlet gas passage communicating with said bore below said valve seat, said cylinder having perforations leading to said valve seat and communicating with said gas inlet passage, said cylinder having an inner passage leading from said valve seat to a position below said first end of the hollow body portion; a valve for engagement with said valve seat, said cylinder having holes extending laterally from said latter passage, said cylinder having a flange spaced below 100 said first end of the body portion; a collar rotatably surrounding said cylinder and interposed between said flange and said first end of the body portion, said collar having holes adapted to register with said holes in the cylinder for regulating the amount of air passing through said first passage of the cylinder, said body portion having an outlet passage communicating with said mixing chamber, said valve having a rod depending through said first passage of the cylinder and through a hole in the lower end of said cylinder; and means detachably secured to the lower end of said rod and of larger cross section than said latter hole whereby suction established in said outlet passage can lift the valve from its seat a distance prescribed by the normal distance 115 of said means on the rod from the lower portion of said cylinder; substantially as described.

3. A carbureter including a body portion having a bore extending inwardly from one 120

end and stopping short of the other end; a cylinder adapted to fit within said bore and having a valve seat spaced from the inner end of the bore to provide a mixing chamber, 5 said body portion including an inlet gas passage communicating with said bore below said valve seat, said cylinder having perforations leading to said valve seat and communicating with said gas inlet passage, said cylinder 10 having an inner passage leading from said valve seat to a position below said first end of the hollow body portion; a valve for engagement with said valve seat, said cylinder having holes extending laterally from said 15 latter passage, said cylinder having a flange spaced below said first end of the body portion; a collar rotatably surrounding said cylinder and interposed between said flange and said first end of the body portion, said col-

lar having holes adapted to register with 20 said holes in the cylinder for regulating the amount of air passing through said first passage of the cylinder, said body portion having an outlet passage communicating with said mixing chamber; and a set screw 25 in said body portion engaging said cylinder for holding the latter in place whereby when the set screw is removed the cylinder, collar and valve can be removed as a whole from said bore; substantially as described. 30

In testimony whereof I have signed my name to this specification in the presence of two subscribing witnesses.

JOHN SCHOLTZ.
